UNITED STATES PATENT OFFICE.

LEWIS E. WATERMAN, OF ROCKFORD, ILLINOIS, ASSIGNOR TO EMERSON MANUFACTURING COMPANY, OF ROCKFORD, ILLINOIS, A CORPORATION OF ILLINOIS.

WHEELED PLOW.

No. 823,244.

Specification of Letters Patent.

Patented June 12, 1906.

Application filed January 18, 1906. Serial No. 296,721.

To all whom it may concern:

Be it known that I, LEWIS E. WATERMAN, a citizen of the United States, residing at Rockford, in the county of Winnebago and State of Illinois, have invented certain new and useful Improvements in Wheeled Plows, of which the following is a specification.

The object of this invention is to construct a wheeled plow in two or more sections having a flexible connection in a vertical direction.

The further object of this invention is to provide a single furrow-wheel and a single land-wheel serving to support the rear end of the forward section and the forward end of the next rear section.

The further object of this invention is to form a connection between a land-wheel and a furrow-wheel in order that the movements of the wheels will be in unison.

The further object of this invention is to hold the land and furrow wheels parallel with the length of the frames of the plow in order that in transporting the plow over the field its width will be greatly reduced and a single hitch to the plow will answer.

The further object of this invention is to construct the lifting arrangement for the furrow-wheels so that the lever thereof may be turned in different positions in order that it may be reached from the gang-planks forming a walkway.

In the accompanying drawings, Figure 1 is a plan view of my improved wheeled plow with the parts in working position. Fig. 2 is a plan view of the plow with the parts in position for transportation over the field or on the road. Fig. 3 is a plan view of one of the furrow-wheels. Figs. 4 and 6 are elevations of the support for the furrow-wheels. Fig. 5 is a transverse section on dotted line *a a*. Fig. 1, showing the swivel arrangement. Fig. 7 is a plan view of one of the land-wheels. Fig. 8 is an elevation of one of the land-wheels. Fig. 9 is an isometrical representation of the bracket 50. Fig. 10 is a section on dotted line *b b*, Fig. 1. Fig. 11 is a section on dotted line *c c*, Fig. 1. Fig. 12 is an isometrical representation of a section of the main bar of the main frame.

In Figs. 1 and 2 of the drawings all of the details of construction of the supports for the land and furrow wheels are not shown, but

are more fully shown in other figures of the drawings.

In the make of a steam-plow it is designed to employ two or more sections directly connected together, each section supporting a series of plows, and I have deemed it necessary to show only two sections, and these are not shown their full length.

The main frame of all the sections are the same, also the attachment of the disks thereto, and in this instance only two sections being employed they will be designated "front" and "rear" sections.

The main bar 1 of the main frame is in T form and extends in the lengthwise direction of a section. The flat portion of the bar forms the upper surface.

A bar 2, located on edge, is held separated from the main bar 1 by the spools 3, through which bolts pass, thereby connecting the bars. The front end of the bar 2 is connected to the vertical web of the main bar 1, and its rear end 4 is turned at right angles to the main portion.

A rear end bar 5 is secured to the end 4, and a bracket arm 6 is secured to this rear end bar, also to the vertical web of the main bar 1.

A series of disks 7 are each connected to the vertical web of the main bar 1 by a bracket 8, with the exception of the rear disk, which is connected to the rear end bar 5.

A gang-plank 9 is located over the main frame and forms a walkway for the attendant manipulating the various levers of the plow. To the gang-plank of the rear section is secured a seat 10 for the attendant.

To the front end of the main frame of the rear section is secured an eye 11, which encircles the rear end bar 5 of the front section, and a loop 12, secured to the rear end bar of the front section holds the eye in place.

To the forward end of the bar 2 of the rear section is bolted a brace 13, having its forward end connected to the rear end bar 5 of the forward section by the means shown in section at Fig. 10. The front end of the brace 13 has a vertically-elongated opening 14, within which is located a bushing 15. A bolt 16, washer 17, and nut 18 clamp this bushing to the rear end bar of the front section. The elongated opening 14 in the brace permits this end of the brace to have a verti-

cal movement in connection with the forward section. To the forward end of the main frame of the forward section is secured a bracket 19, to which a link 20 is pivotally connected, and the free end of this link has a connection with the cross-beam 21, to which the engine is attached by the chain 22. The three furrow-wheels and their supports are of like construction, with the exception of the brackets connecting the supports with the main frame, the bracket for the front furrow-wheel of the front section differing from the other brackets, and at Figs. 3, 4, 5, and 6 the bracket shown is for the two rear furrow-wheels. The bracket 23 has a tubular section 24 located in a vertical position and has its upper section provided with two ribs 25, separated a suitable distance.

A furrow-wheel support 26 is located in the tubular section 24 of the bracket 23, and on its lower end is located a furrow-wheel 27 in a manner to permit it to revolve independent of its support. Around the upper end of the furrow-wheel support 26 is located a toothed quadrant 28 in a manner to permit it to turn axially. A pin 29 passes through the support 26 above the toothed quadrant 28, and a pin 30 passes through the support 26 below the toothed quadrant. These pins 29 and 30 locate the toothed quadrant on the support 26.

A semicircular band 31 is located in connection with the tubular section 24 of the bracket 23 and is located between the ribs 25. A U-bolt 32 is placed around the tubular section 24 between the ribs 25, having its ends passing through holes in the semicircular band 31 and receives nuts 33 on their projecting ends.

A hand-lever 34 has a pivotal connection 40 with the toothed quadrant 28 by the bolt 35 and has an end 36 extending beyond the pivotal point. This hand-lever is provided with the usual dog engagement with the toothed quadrant.

Two links 37 have their upper ends pivotally connected to the hand-lever extension 36, and their lower ends are pivotally connected to the semicircular band 31.

A coiled spring 38 has one end connected 50 to the hand-lever 34, and its other end has a connection with the semicircular band 31 through the link 39.

By loosening the U-bolt 32 the semicircular band 31 may be turned axially around the tubular section 24 of bracket 23 and again clamped in position. This adjustment of the semicircular band will locate the hand-lever 34 in any position desired in order that the attendant may reach it from the gang-plank. 55 By means of the hand-lever 34 that end or ends of the sections controlled by the furrow-wheel with which the hand-lever has a connection may be raised or lowered to present the disks in proper working position or elevate them for transportation over the field or 60

on the road. The coiled spring 38 is connected with the hand-lever and serves to assist the attendant in elevating the main frame of the plow.

From the furrow-wheel support 26 extends 70 an arm 40 and has a fixed connection with the support. This arm 40, projecting from the support for the furrow-wheel, located at the forward end of the front section, extends forward from the support, and the arms for the 75 remaining furrow-wheels extend rearward from their supports.

The bracket 41 for the furrow-wheel, located at the forward end of the front section, is bolted to the vertical web of the main bar 80 of the main frame, and the brackets supporting the remaining furrow-wheels are secured to the projecting end of the end bar 5 of the main frame of each section. To the forward end of the front section is secured an angle-bracket 85 42^a, and a brace 43 connects this bracket with the forward end of the main bar 1 of the main frame. As the land-wheels and their bracket-supports are all of the same construction, a description of one will answer and are shown in detail at Figs. 7, 8, and 9. A toothed quadrant 44 has two ears 45 and 46. From each ear extends a side wing 47, which is provided with a hole 48. From the toothed quadrant 44 extends a vertical 95 rib 49.

A bracket 50 has a vertical tubular section 51, a slotted end 52, and two ribs 53. A hole 54 is formed through the bracket proper, through which an eyebolt 55 passes, connecting it with the rear end bar 5 of both sections and with the angle-bracket 43 of the front section.

The surface of the slotted end 52 is serrated, and a bolt 56 passes through the slot 105 and connects that end of the bracket with the rear end bar 5 of both sections and with the angle-bracket of the front section.

The ears 45 of the toothed quadrant 46 receive the tubular section 51 of the 110 bracket 50 between them, and a pin 57 passes through the holes in the ears and through the tubular section, thereby forming a pivotal connection between the toothed quadrant and the bracket 50. A cranked 115 axle 58 has one end supported in a bearing 59, formed in the toothed quadrant 44, and its other end supports a land-wheel 60. A hand-lever 61 has a pivotal connection with the cranked axle 58 and is provided with the 120 usual dog engagement with the toothed quadrant. A coiled spring 62 has one end connected to the hand-lever, and its other end is connected to the toothed quadrant 44. A rod 63 has its upper end pivoted to the hand-lever 61 and its lower end passing through an eye 64, secured to the sand-box 65, connected to the cranked axle 58. A pin 66 is inserted in a hole in the end of the rod 63, projecting below the eye 64, and a spring 66 sur- 130

rounds the rod 63 above the eye 64. The rod 63 forms the connection between the hand-lever and cranked axle, by which the side of the main frame supported by the land-wheels is raised and lowered. The coiled spring 66 permits a yielding movement of the land-wheel, and the spring 62 will assist the attendant in raising the main frame and plows attached thereto.

10 As the land-wheel 60 is to one side of the pivotal pin 57, the tendency of the wheel is to caster into the line of draft; but when the plow is in working position, as shown at Fig. 1, the rib 49 of the toothed quadrant 44 will rest in contact with the ribs 53 of bracket 50, thereby preventing further caster movement of the land-wheel.

When the plow is transported over the field or on the road, the furrow-wheels are placed 20 in the positions shown at Fig. 2, in which a pin 67 is placed in the holes 48 in the ear extensions 47, and the pin will come in contact with the ribs 53, extending from the bracket 50, which will hold the furrow-wheel at substantially right angles to the bracket. The pin 67 when not in use is placed in holes in the ears 45 and 46 of the toothed quadrant 44, as shown at Figs. 7 and 8. From the toothed quadrant 44 extends a stud 68. The 30 furrow and land wheels supported by the rear end bar 5 of the front section are connected by the rod 69, having one end connected to the stud 68 of the toothed quadrant of the land-wheel and its other end connected to the arm 40, extending from the furrow-wheel support. The furrow and land wheels supported by the rear end bar 5 of the rear section are similarly connected by the rod 70.

40 By means of the rods 69 and 70 furrow-wheels connected thereto are controlled by the movements of the land-wheels connected to the other ends of the rods, and are held in working position or in position for transportation.

45 The furrow-wheel connected to the front end of the front section is guided in its movements by the link 71, connecting the arm 40, extending from the furrow-wheel support, 50 with the draft-link 20, as shown at Figs. 1 and 2. A hitch is made between the beam 21 and the eye-bolt 55, connected with the rear end bar 5 of the front section by the chain 72, and the engine has a connection 55 with the ring 73, which is connected to the beam by the chains 22.

In transporting the plow over the field or on the road the engine is attached to the chain 74, Fig. 2, which will bring the link 20 into 60 the line of draft and through the link 71. The front furrow wheel is held in the line of draft. By this construction of plow a single furrow-wheel and a single land-wheel are located at the rear end of one section and the front end 65 of the following section.

By connecting the sections by the brace 13 they are held in proper alignment so that the sections cannot crowd each other in turning corners; neither can one lag behind the other. In fact, they act as a single plow in these respects, but have a limited vertical movement at their points of connection to accommodate any unevenness of the ground.

I claim as my invention—

1. In a wheeled plow, the combination of a 75 series of end-connected sections, wheels supporting the sections, a series of plowing attachments supported by each section, each section composed of two bars extending lengthwise of the section, braces holding the 80 bars separated, and an end bar for each section.

2. In a wheeled plow, the combination of a 85 series of end-connected sections, wheels supporting the sections, a brace connected with the forward end of each section in rear of the first section and connected to the section next in front in a manner to prevent lateral movement, and a series of plowing attachments supported by each section.

3. In a wheeled plow, the combination of a 90 series of end-connected sections, wheels supporting the sections, a series of plowing attachments supported by each section, a draft-evener, and two connections between the 95 draft-evener and the front section, one of the connections attached near the forward end of the section, and the other connection attached near the rear end of the section.

4. In a wheeled plow, the combination of a 100 series of end-connected sections held substantially rigid against lateral movement and capable of vertical oscillation at the point of connection, wheels supporting the sections, a series of plowing attachments supported by 105 each section, the sections located in the same lengthwise direction but in different lateral planes.

5. In a wheeled plow, the combination of a 110 series of directly-connected sections held substantially rigid against lateral movement and capable of vertical oscillation at the point of connection, wheels supporting the sections, a series of plowing attachments supported by 115 each section, the sections located in the same lengthwise direction but in different lateral planes.

6. In a wheeled plow, the combination of a 120 series of end-connected sections, a series of plowing attachments supported by each section, wheels supporting the sections and having a pivotal connection therewith and capable of being located in working position, or located parallel with the length of the sections.

7. In a wheeled plow, the combination of a 125 series of end-connected sections, a series of plowing attachments supported by each section, wheels supporting the sections having a pivotal connection therewith and means re- 130

taining the wheels in working position, or parallel with the length of the sections.

8. In a wheeled plow, the combination of a series of end-connected sections, a series of plowing attachments supported by each section, wheels supporting the sections and having a pivotal connection therewith, means retaining the wheels either in working position or parallel with the length of the sections, and a hitch on the front section.

9. In a wheeled plow, the combination of a series of end-connected sections, wheels supporting the sections, a series of plowing attachments supported by each section, the sections located in the same lengthwise direction but in different lateral planes.

10. In a wheeled plow, the combination of a series of directly-connected sections, wheels supporting the sections, a series of plowing attachments supported by each section, the sections located in the same lengthwise direction but in different lateral planes.

11. In a wheeled plow, the combination of a series of end-connected sections, wheels supporting the sections, a series of plowing attachments supported by each section, the plowing attachments of all the sections located in the same general lengthwise direction, the plowing attachments of a section located laterally with respect to the plowing attachments of the other sections.

12. In a wheeled plow, the combination of a series of directly-connected sections, wheels supporting the sections, a series of plowing attachments supported by each section, the plowing attachments of all the sections located in the same general lengthwise direction, the plowing attachments of a section located laterally with respect to the plowing attachments of the other sections.

13. In a wheeled plow, the combination of a series of connected sections, wheels supporting the sections, and a series of plowing attachments supported by each section, the plowing attachments of all the sections located in the same general lengthwise direction, the plowing attachments of a section located laterally with relation to the plowing attachments of the other sections, one of the wheels being a furrow-wheel and located between the last plowing attachment of a forward section and the front plowing attachment of the next rear section.

14. In a wheeled plow, the combination of a series of end-connected sections, wheels supporting the sections, and a series of plowing attachments supported by each section, the plowing attachments of all the sections located in the same general lengthwise direction, the plowing attachments of a section located laterally with relation to the plowing attachments of the other sections, one of the wheels being a furrow-wheel and located between the last plowing attachment of a for-

ward section and the front plowing attach- 65
ment of the next rear section.

15. In a wheeled plow, the combination of a series of connected sections, a series of plowing attachments supported by each section, one of the wheels supporting the sections, one of the wheels being a furrow-wheel and located adjacent to the rear end of one section and the forward end of the next rear section.

16. In a wheeled plow, the combination of a series of end-connected sections, a series of plowing attachments supported by each section, a series of wheels supporting the sections, one of the wheels being a furrow-wheel and located adjacent to the rear end of one section and the forward end of the next rear section.

17. In a wheeled plow, the combination of a series of connected sections, a series of plowing attachments supported by each section, and a number of land and furrow wheels supporting the sections, there being one more furrow-wheel than the number of sections.

18. In a wheeled plow, the combination of a series of end-connected sections, a series of plowing attachments supported by each section, and a number of land and furrow wheels supporting the sections, there being one more furrow-wheel than the number of sections.

19. In a wheeled plow, the combination of a series of connected sections, a series of plowing attachments supported by each section, a single land-wheel, and a single furrow-wheel serving to support the rear portion of one section and the forward portion of another section.

20. In a wheeled plow, the combination of a series of connected sections, a series of plowing attachments supported by each section, a single land-wheel and a single furrow-wheel serving to support the rear portion of one section and the front portion of another section, and a connection between the wheels.

21. In a wheeled plow, the combination of a series of connected sections, a series of plowing attachments supported by each section, a land-wheel and two furrow-wheels connected to the forward section, and a single land-wheel and a single furrow-wheel connected to each other section.

22. In a wheeled plow, the combination of a series of connected sections, a series of plowing attachments supported by each section, a land-wheel and two furrow-wheels connected to the forward section, a connection between the land and rear furrow wheels, a single land-wheel and a single furrow-wheel connected to each other section, and a connection between the last-mentioned wheels.

23. In a wheeled plow, the combination of a series of connected sections, a series of plowing attachments supported by each section, two land-wheels and two furrow-wheels

connected to the front section, and a single land-wheel and single furrow-wheel connected to each other section.

24. In a wheeled plow, the combination of a series of connected sections, a series of plowing attachments supported by each section, two land-wheels and two furrow wheels connected to the forward section, a connection between the rear land and furrow wheels of the forward section, a single land-wheel and a single furrow-wheel connected to each other section, and a connection between the wheels of each other section.

25. In a wheeled plow, the combination of a series of connected sections each capable of a vertical oscillation, a series of plowing attachments supported by each section, a single land-wheel and a single furrow-wheel serving to support the rear portion of one section and the forward portion of another section.

26. In a wheeled plow, the combination of a series of connected sections each capable of a vertical oscillation, a series of plowing attachments supported by each section, a single land-wheel and a single furrow-wheel serving to support the rear portion of one section and the forward portion of another section, and a connection between the wheels.

27. In a wheeled plow, the combination of a series of connected sections, a series of plowing attachments supported by each section, a single land-wheel, a single furrow-wheel, each having a caster movement and

serving to support the rear portion of one section and the forward portion of another section, a connection between the wheels, and means for locking one of the wheels against caster movement.

28. In a wheeled plow, a plow-supporting frame, a furrow-wheel support, a furrow-wheel, a toothed quadrant capable of a swivel movement but held against lengthwise movement in connection with the furrow-wheel support, a collar having a swivel connection with the frame, a hand-lever pivotally connected to the toothed quadrant, a link forming a connection between the collar and hand-lever, and a spring having one end connected to the collar and its other end attached to the hand-lever.

29. In a wheeled plow, a plow-supporting frame, a wheel-support, a wheel, a toothed quadrant capable of a swivel movement but held against lengthwise movement in connection with the wheel-support, a collar having a swivel connection with the frame, a hand-lever pivotally connected to the toothed quadrant, a link forming a connection between the collar and hand-lever, and a spring having one end connected to the collar and its other end attached to the hand-lever.
